UNITED STATES PATENT OFFICE

152,138

DESIGN FOR A SKIRT ENSEMBLE OR SIMILAR ARTICLE OF WEARING APPAREL

Oscar H. Cohen, Brighton, Mass., assignor to Century Sportswear Co., Inc., Boston, Mass., a corporation of Massachusetts

Application May 12, 1948, Serial No. 146,326

Term of patent 3½ years

(Cl. D3—26)

To all whom it may concern:

Be it known that I, Oscar H. Cohen, a citizen of the United States of America, residing at 21 Wiltshire Road in Brighton, county of Middlesex, and Commonwealth of Massachusetts, have invented a new, original, and ornamental Design for a Skirt Ensemble or Similar Article of Wearing Apparel, of which the following is a specification, reference being had to the accompanying drawings, forming a part thereof.

Fig. 1 is a front view of a skirt ensemble embodying the new design, as it appears when worn;

Fig. 2 is a side view of the skirt ensemble as seen from the right side of Fig. 1;

Fig. 3 is a perspective view of the skirt ensemble as seen when looking toward the front from the right side; and

Fig. 4 is a front view of the upper portion of the skirt ensemble unfastened and separated from the lower portion thereof.

I claim :

The ornamental design for a skirt ensemble or similar article of wearing apparel, substantially as shown and described.

OSCAR H. COHEN.
